UNITED STATES PATENT OFFICE.

WILLIAM M. DUNCAN, OF ALTON, ILLINOIS.

FURNACE-GRAVE.

1,088,773.

Specification of Letters Patent.

Patented Mar. 3, 1914.

Application filed July 18, 1912. Serial No. 710,140.

To all whom it may concern:

Be it known that I, WILLIAM M. DUNCAN, a citizen of the United States of America, and resident of Alton, in the county of Madison and State of Illinois, have invented certain new and useful Improvements in Furnace-Grates, of which the following is a full, clear, and exact description, reference being had to the accompanying drawings, forming a part of this specification.

My invention relates to a furnace grate and has for its object the production of a grate bar through which air under pressure may be conducted to the bed of fuel supported by the grate.

The preferred form of my invention is a mechanical stoker comprising endless grate bar chains and hollow grate bars between said chains. The hollow grate bars are provided with discharge openings located in a higher plane than the top surfaces of the grate bar chains, and air under pressure supplied to the hollow grate bars is forced through said openings and into the bed of fuel, with the result of causing the entire bed of fuel to be consumed. This is a decided advantage over the ordinary grates relying on natural draft or forced draft directed onto the fuel from a point some distance away from the grate, because the air so supplied cannot penetrate through the entire bed of fuel—it cannot reach the fuel immediately above the grate bars—and as a result an appreciable percentage of the fuel is never consumed.

It will be noted that air under pressure discharged from my improved grate bar must pass directly into the fuel bed; it cannot take any other course, and this air penetrating the entire bed of fuel will furnish the oxygen necessary for perfect combustion.

Figure I is a vertical section of a grate embodying the features of my invention. Fig. II is a transverse section of a portion of the grate. Fig. III is a perspective view of one of the grate bars.

In the accompanying drawings: 1 designates side frames supporting a drive shaft 2, provided with drive wheels 3 and also an idle shaft 4, provided with plain wheels 5. Endless grate chains 6 passing around

the wheels 3 and 5 ride over rollers 7 and 8 when the drive shaft is rotated.

9 and 10 designate transverse rods supporting the rollers 7 and 8 respectively.

A designates hollow grate bars arranged directly between certain side walls of the grate chains, and supported partly by the transverse rods 9, and partly by a manifold 11. The rods 9 pass through sleeves 12 formed integral with the hollow grate bars

A. The manifold 11 has flanged ends that are secured to the side frames 1, one end of said manifold being closed by a manhole cover 13 secured to one of the side frames, (see Fig. II). Each hollow grate bar A is secured to the manifold and provided with a bottom opening 14, which registers with a corresponding opening in the top of the manifold. Air under pressure may be conducted to the manifold through a pipe 15, (Fig. II), and after passing through the manifold and into the hollow grate bars, the air is discharged through openings 16 in the upper portions of the hollow grate bars. It will be noted that the hollow grate bars are closed to prevent the escape of air through their side and bottom walls and that the discharge openings 16 are located in a higher plane than the top surfaces of the grate chains 6, hence the air is discharged into the fuel immediately above the grate chains.

The means for cleaning out the hollow grate bars comprises scrapers 17 located in said bars beneath the plane of the top of the manifold and provided with long handles 18 which extend across the manifold to the front of the grate structure where they may be very easily reached by the operator. Ashes, etc., which accumulate in the hollow grate bars can be easily drawn into the manifold by means of the scraper 17 and afterward removed from the manifold through the opening that is normally closed by the manhole cover 13.

I claim:—

A furnace grate comprising side walls, a drive shaft having a drive wheel, an idle shaft having a driven wheel, and two series of transverse rods; said drive shaft, idle shaft and series of rods being mounted in the said side walls, series of rollers mounted on the rods, endless grate chains mount-

ed on said wheels and series of rollers, a manifold having a compressed air inlet and air outlets and located between the two series of rollers, and hollow grate bars located between the endless grate chains and connected with the air outlets of the manifold, each of the grate bars being formed with openings in the top thereof through which

compressed air is discharged into the fuel and with sleeves through which certain of 10 said rods pass.

WILLIAM M. DUNCAN.
